US0D1081419S

(12) **United States Design Patent** (10) Patent No.: **US D1,081,419 S**
(45) Date of Patent: ** Jul. 1, 2025

(54) **GPS RECEIVER**

(71) Applicant: **Huanlian Wu**, Shantou (CN)
(72) Inventor: **Huanlian Wu**, Shantou (CN)
(**) Term: **15 Years**
(21) Appl. No.: **29/931,053**
(22) Filed: **Mar. 5, 2024**
(51) LOC (15) Cl. **10-04**
(52) U.S. Cl. **USPC D10/70; D10/65**

CLAIM

The ornamental design for a GPS receiver, as shown and described.

DESCRIPTION

FIG. 1 is a front, right and top perspective view of a GPS receiver showing my new design;

FIG. 2 is a rear, left and bottom perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines depict portions of the GPS receiver and form no part of the claimed design.

1 Claim, 8 Drawing Sheets
